UNITED STATES PATENT OFFICE.

LINN B. HARROD, OF LITTLE ROCK, ARKANSAS.

CARBURETER ATTACHMENT.

1,250,451.

Specification of Letters Patent. Patented Dec. 18, 1917.

Application filed March 28, 1917. Serial No. 157,916.

To all whom it may concern:

Be it known that I, LINN B. HARROD, a citizen of the United States, and a resident of Little Rock, in the county of Pulaski and State of Arkansas, have made, certain new and useful Improvements in Carbureter Attachments, of which the following is a specification.

My invention relates to improvements in attachments for carbureters, and it consists in the combinations, constructions and arrangements herein described and claimed.

My invention relates more particularly to means for heating the air coming through the air intake of a carbureter thereby facilitating the starting of the engine with which the carbureter is associated.

A further object of my invention is to provide an attachment to the carbureter which is simple in construction but by means of which the incoming air may be heated through electrical means, at the will of the operator.

Other objects and advantages will appear in the following specification, and the novel features of the invention will be particularly pointed out in the appended claim.

My invention is illustrated in the accompanying drawings which form part of this application, and in which:

Figure 1 is a side view of the device as applied to a carbureter.

Fig. 2 is a central section through the device, and

Fig. 3 is a section along the line 3—3 of Fig. 2.

In carrying out my invention, I provide an insulating cylinder 1 which may be fiber or other suitable insulating material, this cylinder being secured to the end of the air intake pipe 2 by screws 3 or in any other suitable manner. At the end of the cylinder 1 is a cap 4 which is provided with wire mesh 5 so as to strain the air entering the pipe.

On the inside of the tube 1 is an asbestos lining 6. This is in the shape of a tube which is in engagement with the tube 1. In-

stead of making the tube 6 of asbestos, porcelain or other suitable material might be used.

On the inside of the tube 6 is a resistance element 7 which in the present instance is shown as consisting of two or three spirals of wire such as German silver wire or other suitable resistance element. The ends of the resistance element 7 are brought out to the binding posts 8 to which wires 9 are attached. The wires 9 may be connected with any suitable source of current.

From the foregoing description of the various parts of the device, the operation thereof may be readily understood. When it is desired to heat the air entering the air intake, current is sent through wires 9, thus heating the resistance element which in turn imparts its heat to the air.

The mixture of heated air and gasolene is more easily ignited than a cold mixture, and the engine will start many times with the use of this attachment, as for instance in cold weather, when it would not start under ordinary conditions.

I claim:

A carbureter attachment comprising an insulating tube having one end arranged to slip over the air intake tube of the carbureter, means for securing said insulating tube to said air intake tube, a heat resisting tube disposed within said first-named tube, an electrical resistance element disposed within said heat resisting tube, said element comprising a series of spiral coils, the planes of the coils being parallel and being at right angles to the central axis of the tube, terminals carried by the first-named tube and connected with the ends of said resistance element, and a strainer at the opposite end of the first-named tube from the carbureter intake tube for straining the air prior to its heating by said resistance element.

LINN B. HARROD.
